(54) **SAW MILL, DOGS**

(76) Inventor: **Martin Rich**

Martin Rieh. Condor. New York

Letters Patent

The Schedule referred to in these Letters Patent and making part of the same containing a description in the words of the said Martin Rieh himself of his improvement in Iron dogs for a Saw Mill

I now all men by these presents that I Martin Rieh of the Town of Condor in the County of Tioga & State of New York have made and invented a new and useful improvement in the Iron dogs for a Saw Mill in the words following to wit. The Blocks to which the dogs are made fast are similar to the common head Block now in use. The Dogs are two half Bails on each Block, like those generally used except the following difference. One of the half bails has threethree teeth on the upright part of the dog one at the top and the other at about the centre these teeth must be of sufficient length and width for a screw to pass thro each. Two screws are made of iron about three fourths of an inch in diameter & about four inches long. These screws are for a set or gauge for the sawed side of the log to bear against. A nail about two inches square is put on the end of each screw next to the log. Also a nut on each screw on the other side of the tooth for the purpose of binding the screw if it should ever wear loose. The other teeth in the quarter round are for from the upper tooth on the upright part as to admit the saw. The other half bail is to have three similar teeth except as follows. The upper tooth on the upright part is to be a double tooth that is to say one half of the tooth is to be perpendicular on the edge. The other half horizontal about half an inch shorter. The two upper teeth on the bail about two inches apart. The advantage in the above described dogs over any other now in use is that the boards will all be of an equal thickness. That the saw will run entirely through the log, that it is more convenient to set in the right than any other. What I claim as my improvement is the particular situation & construction of the teeth & the

scree to set the log. In Testimony that the above is a true specification of my said improvement as by me described. I have hereunto set my hand and Seal this twenty third day of December one thousand eight hundred and twenty nine
